(57) CLAIM

The ornamental design for a electric foldable towel warmer, as shown and described.

DESCRIPTION

FIG. 1 is a perspective view from the top of an electric foldable towel warmer;

FIG. 2 is a perspective view thereof from below;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a perspective view thereof in a first alternative configuration;

FIG. 10 is a perspective view thereof in a second alternative configuration;

FIG. 11 is a perspective view thereof in a third alternative configuration;

FIG. 12 is a perspective view thereof in a fourth alternative configuration;

FIG. 13 is a perspective view thereof in a fifth alternative configuration; and,

FIG. 14 is a perspective view thereof in a sixth alternative configuration.
